PUMP

Reginald J. S. Pigott, Pittsburgh, Pa., assignor to
 Gulf Research & Development Company, Pittsburgh, Pa., a corporation of Delaware

Application October 11, 1935, Serial No. 44,626

1 Claim. (Cl. 103—5)

This invention relates to pumps; and it comprises in combination with a pump of the rotary positive displacement type adapted to pump liquids and having two interengaging main pressure pump members, one of which rotates at higher speed than the other, means for raising the pressure of liquid just before delivery into the inlet side of the main pressure pumping members in order to prevent formation of vapor in the pump, 5 10 15 20 25 30 35 40 45

said means comprising a rotary impeller of a type adapted to develop pressure by rotational velocity, the impeller being operatively connected with, and driven by, the main pumping member which runs at the higher speed, the impeller being of larger diameter than either of the two main pumping members, and a casing enclosing the impeller and having an inlet connection for liquid to be pumped delivering to the impeller and also a liquid connection from the impeller to the inlet side of the main pumping members; the impeller and casing therefor in some modifications being adapted for ready attachment to and detachment from the main pressure pump proper and for replacement with a plain head; all as more fully hereinafter set forth and as claimed.

There has recently been developed an improved type of rotary pump having a rotating ring gear and a pinion engaging the ring gear and having one less tooth than the ring gear; the tooth shape being such that during rotation of the two gears a plurality of expanding and contracting chambers are formed in inter-tooth spaces. The two gears are mounted for rotation in a casing which has abutments separating the side of the gear combination wherein the inter-tooth chambers are constantly expanding (inlet side) from the opposite side, in which the chambers are constantly contracting (outlet side). These pumps are highly efficient mechanically and volumetrically. They are of the true positive displacement type and are able to deliver at pressures of several hundred pounds per square inch. The pumps are adapted to run at high speed; speeds around 1200 R. P. M. The pinion for example may be run directly by an electric motor.

In operation the periphery of the ring gear runs at a rather high rate. Liquid entering the pump at a comparatively slow rate is accelerated in the inlet side of the pump, to the peripheral speed of the ring gear. The acceleration is necessarily accompanied by a drop in pressure. In pumping non-volatile liquids, this makes no difference. But in pumping liquids saturated with gas, or liquids almost at their vaporization point, the drop in pressure in the inlet is sometimes

enough to reduce the pressure on the liquid below saturation point or vaporization point, and gas is suddenly evolved from the liquid in the suction side of the pump. The amount of gas evolved is considerable in many cases. In one test on pumping a crude petroleum, the volume of gas evolved in a certain pump of the type described was 25 per cent of the volumetric capacity of the pump.

The presence of gas in the pump while pumping liquids is deleterious. The gas reduces the volumetric capacity and the efficiency of the pump since the pump is under the necessity of acting as a compressor as well as a pump. A further disadvantage is that the gas bubbles as they pass from suction to discharge pressure in the pump are abruptly compressed and collapsed, thereby causing considerable vibration in the oil column on the discharge side of the pump. This effect may give rise to destructive vibration in the pressure piping and is attended by noise and rattle in the pump. The gas evolving effect described is inherent in the operation of rotary positive displacement pumps and is aggravated at high rotational speeds. It may even occur in the case of reciprocating pumps when these are operated at a high piston speed.

One achieved object of the invention is the provision of a ring gear and pinion type pump in which gas formation in the pump is prevented. I do this by providing means for imposing a small plus pressure on the liquid entering the pump; a pressure slightly more than sufficient to overcome pressure drop in the pump due to acceleration. There is provided in combination with the pump, an impeller, of the type adapted to develop a pressure by rotational velocity (the so-called centrifugal or propeller type), which is larger in diameter than the ring and which is rotated directly by the pinion; that is, the member which runs at higher speed. The diameter of the impeller is proportioned so as to be enough larger than that of the ring gear as to compensate for the total pressure drop including that due to acceleration and that due to frictional losses between the impeller and the inlet of the main pump.

In the accompanying drawings are shown more or less diagrammatically, two examples of a specific embodiment of the invention. In the showings,

Fig. 1 is a view in central vertical section of a gear pump provided with an interchangeable booster head;

Fig. 2 is a sectional view taken along line 2-2 of Fig. 1;

Fig. 3 is an end elevation corresponding to Fig. 1;

Fig. 4 is a view partly in elevation and partly in vertical section of the pump of Fig. 1 with the booster head replaced by a plain head;

Fig. 5 is a view in vertical section of one end of a pump provided with a modified booster combination; and

Fig. 6 is a view of the booster impeller of the pump of Fig. 5.

Referring to the figures, in which like reference characters indicate like parts, the pump is shown as comprising a main casing 10 of general horizontal cylindrical form having a substantially cylindrical cavity 8 therein, a vertically extending outlet 11 with fluid conduit 12 therein and a flange 13 for attachment to pipe etc. Casing 10 has an inlet 14 with a similar flange 15, disposed approximately at right angles to the outlet. The casing rests on a rectangular base 16. The pumping members are centrally located in the casing. The ring gear comprises a cylindrical gear member 17 provided with teeth 18 and annular collars 19 at each end. Mounting sleeves 20 are provided at each end of the ring gear, the sleeves being bolted together with the ring gear into a unitary rotor, by a plurality of bolts 25. The outer ends of the mounting sleeves have turned cylindrical extensions 26. The sleeves are mounted for rotation in the casing on ball bearings having fixed races 21, balls 28 and rotary races 29, the rotary races engaging turned portion 26 and the fixed races being retained in annular recesses 30 in the casing. The ring gear is thus retained for free rotation in the casing. The spaces between the ring gear teeth are left open to serve as fluid outlets as indicated at 31, these spaces being in communication with inlet 14 and outlet 12. The casing is provided with a suitable upper abutment 35 and lower abutment 36, engaging the periphery of the ring gear and separating the inlet from the outlet side of the pump.

A pinion 32 is provided engaging the teeth of the ring gear and having one less tooth than the ring gear. The pinion is keyed to a drive shaft 33 by a key indicated at 34. The axis of the drive shaft is eccentric with respect to the axis of the ring gear and of the casing. The drive shaft is rotatably mounted by means of two bearings, shown as roller bearings 40 having sleeves 41 tightly fitted to the drive shaft. At the right end of the pump (Figs. 1 and 4) a head 42 is provided, of roughly conical form and bolted in fluid tight connection to casing 10 by means of bolts 43. The head has a bore 44 surrounding shaft 33, containing packing 45 and stuffing nut 46 to prevent leakage around the shaft. A locking ring or washer 49 for bearing 40 and lock nut 50 threaded on shaft 33 as at 48 are provided as shown.

At the left hand end of the pump is provided the booster combination. An irregular head 55 having an annular flange 56 is bolted to casing 10 in fluid tight connection by means of bolts 43. Head 55 has a cylindrical bore 57 concentric with the axis of the pinion and drive shaft and containing second bearing 40 mounted on shaft 33 by sleeve 41 in frictional fit with the shaft. Thus the pinion and shaft are firmly mounted for rotation at two spaced points. A ring 58 is provided between flange 56 and casing 10, to retain bearings 40 and 27 in place. A thin sleeve 59 spaces left hand sleeve 41 from the pinion.

The end head 55 has attached thereto a hous-

ing of irregular shape 60 with a circular flange 61 provided with holes 62, for attachment of pipe etc., a volute chamber housing portion 63 and a circular flange 64 merged with the volute, as shown. Housing 60 is attached to head 55 at flange 64, by studs and nuts 64. Housing 60 has a divergent conical inlet 65, coaxial with the pinion and drive shaft and delivering into the volute chamber 66 enclosed by portion 63. Member 55 has a frustoconical projection 67 with a bore 68 closely but freely fitting a threaded extension shaft 69 firmly attached to shaft 33 by a threaded connection as at 10. The outer end of extension 69 has a shank of reduced diameter 75 and a tip 76, threaded as shown. Mounted on shank 75 is an impeller 77, keyed thereto as at 78 and retained by a rounded cap nut 79 threaded on tip 76. The impeller has a plurality of angularly disposed blades 80. The cap 79, the inter-blade portion of the impeller and projection 67 merge into a smooth and rounded shape as is apparent in Fig. 1. The blades of the impeller extend towards chamber 66 leaving a slight clearance 85 adjacent the junction of inlet 65 with chamber 66. The diameter of the impeller is greater than the diameter of the ring gear.

Volute chamber 66 has an outlet 86 with outlet passage 87. Outlet 86 has a flange 88. A double bent conduit 89 having flanges 90 at each end is bolted as at 150 to outlet 86 and to the flange 15 of the pump inlet. Thus the impeller draws from inlet 65 and delivers through outlet 86, conduit 89 and inlet 14 to the main pump.

In operation, the pump is driven through drive shaft 33 by an electric motor or other power means (not shown) at a fairly high speed. Inlet 65 being in communication with liquid, impeller 77 draws liquid into volute chamber 66 and delivers liquid under slight pressure to the inlet of the pump proper. The rapidly rotating ring gear 40 and pinion combination 17, 32 tends to reduce pressure at the pump inlet; but since the liquid is under sufficient positive pressure, there is no net drop. Liquid is delivered through outlet 12.

When gassy liquids are pumped, liquids are kept under pressure from the moment they reach inlet 65 and there is no chance for evolution of gas. The pump runs quietly and smoothly at high efficiency.

The diameter of the impeller is made a little larger than that merely necessary to compensate for pressure drop due to acceleration, so as to also compensate for frictional losses in the fluid conduits 87, 89 and 14 and still provide a slight plus pressure in the main pump inlet.

The booster head shown is readily interchangeable with an ordinary head in case it is desired to dispense with the booster. Referring to Fig. 4, a simple cap-like head 100 is provided, having a flange 101 similar to flange 56 on the booster head and retained to the casing by bolts 43. The head has a bore 102 of the same size as the bore 57 in the booster head, and bearing 40 is retained therein, a retaining shoulder 102 being provided. Threaded bore 70 is advantageously utilized in this modification, to supplement friction in retaining the shaft in the bearing sleeve 41. As shown, a retaining bolt 99 is provided, engaging the threads in the shaft end and engaging a retaining ring 149, similar to ring 49 shown at the right hand end of Fig. 1. However, the bolt and ring can often be omitted; frictional contact between the bearing sleeve and the shaft being sufficient.

In replacing the booster head with the plain

head, it is merely necessary to take off the booster head containing its bearing 40 and unscrew extension 69, and then slip on plain head 100 with its bearing 40. Sometimes, instead of providing the threaded extension 69, it is more convenient to make shaft portion 69 and 33 in one piece, the entire shaft in this case being taken out and replaced with a shorter one when the change is made.

10 In the embodiment of the invention described, the booster impeller is of the propeller type. Sometimes it is more convenient to employ a centrifugal type booster impeller. Figs. 5 and 6 illustrate such a modification. The booster casing is made in two pieces: a bearing housing 110 and a centrifugal volute housing 111 attached thereto. The volute housing has an inlet portion 112 flanged as at 61, and a volute chamber 113 of the typical shape for centrifugal devices. Shank 69 of unitary shaft 109 is mounted in housing 110 by bearing 40. Extension 75 is provided with a centrifugal impeller, comprising a discoid hub 114 and radial blades 115, retained on the shaft by a nut 116 and a key 118. A spacing disk 117 separates the impeller from bearing 40. The outlet 87 of volute chamber 115 is in communication with the inlet of the pump as described in connection with the propeller modification. The

diameter of the centrifugal impeller is considerably greater than that of the ring gear.

In operation, the centrifugal impeller boosts the pressure, to produce the same effect as described in the case of the propeller modification. 5

What I claim is:

A pump of the rotary positive displacement type having a chambered casing provided with an inlet and an outlet, a pinion and ring gear serving as pumping members, the pinion rotating 10 at higher speed than the ring gear, means for rotatably mounting the ring gear in the casing, a shaft secured to the pinion, a head at each end of the casing, bearing means in each of said heads for the shaft, an impeller of a type adapted to develop pressure by rotational velocity in one of the heads, a detachable shaft extension on the end of the shaft extending into said head, the impeller being secured to the shaft extension, 15 an impeller housing surrounding the impeller and having an inlet connection delivering liquid to the impeller and having also a detachable outlet connection from the impeller to the inlet side of the gears, and means for detachably securing the impeller housing and head to the casing, so that 20 the head, bearing therein, housing, impeller and shaft extension can be removed from the casing. 25

REGINALD J. S. PIGOTT.
